UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

EXPRESSION MECHANISM FOR MUSICAL INSTRUMENTS.

1,409,489.

Specification of Letters Patent. Patented Mar. 14, 1922.

Application filed October 3, 1916, Serial No. 123,464. Renewed February 11, 1921. Serial No. 444,264.

To all whom it may concern:

Be it known that I, CHARLES F. STODDARD, a citizen of the United States, residing in the city of New York, county and State of New

5 York, have invented an Improvement in Expression Mechanism for Musical Instruments, of which the following is a specification.

This invention relates to apparatus for 10 automatically varying playing intensities in automatic musical instruments, such, for instance, as player-pianos and the like.

Among other objects, the invention is intended to provide apparatus capable of producing prompt changes in playing intensity 15 while maintaining intensities so far as may be desired, regardless of the number of tones sounded.

The character of the invention may be 20 readily understood by reference to the accompanying drawings, wherein—

Figure 1 shows diagrammatically one illustrative embodiment thereof, and

Figure 2 is a detail section on the line 25 2—2 of Figure 1.

In the drawings, a bellows 1 exemplifies a source of power for operating the striker pneumatics which may be operated selectively, as well understood by those skilled in 30 the art, from a tracker board through ducts 3. A passage 4 connects the action chests 5 of the player actions with a port 6 into a regulating pneumatic 7 having a regulator valve 8 controlling a port 9 communicating 35 with the source of power 1. The regulator valve 8 is connected by a link 10 with the movable board of the regulator pneumatic 7. As well understood in the art, the valve 8 regulates the flow of air from the action 40 chests 5 to the source 1.

The regulator pneumatic is provided with a spring 11 fastened thereto preferably near one end of the movable board thereof, for example, at the left in Figure 1 of the drawings. The other end of the spring may be 45 adjustably fastened to some stationary part of the instrument so that the spring will be adapted to exert a substantially constant pull upon the regulator pneumatic. Tracks 50 14 are fastened to the underside of the movable board of the regulator pneumatic and extend preferably from about the center thereof to the end opposite the point of attachment of the spring 11, i. e. to the right 55 in the drawings. A block 15, mounted to

slide in a stationary guideway 16, carries a pair of rollers 17 mounted upon a transversely extending shaft 18 and adapted to run in the tracks 14.

The movable board of the regulator pneumatic 7 is freely movable about the rollers 17 as a fulcrum under the control of the opposed forces of the spring 11 and the exhaust within the regulator bellows. If, therefore, the position of the fulcrum is 60 changed one of the opposed forces acting upon the regulator bellows will change as the regulating balance is maintained. The tension of the spring, with the exception of such primary adjustments as are necessary, 65 will remain substantially constant within narrow limits, and the variable factor in maintaining the balanced condition of the regulator will therefore be the exhaust within the pneumatic 7. With the fulcrum of 70 the regulating bellows at its greatest distance from the regulator spring the differential between exhaust pressure and atmospheric pressure acting upon substantially the entire area of the movable board of the 75 regulator pneumatic, will be effective to oppose the pull of the spring. This will cause the regulator pneumatic in balanced condition to maintain the degree of exhaust within the regulator pneumatic and the wind 80 trunk leading to the playing pneumatics at a point more nearly approximating atmospheric pressure. If, however, the fulcrum of the regulator pneumatic is moved toward the spring, the effective area acted upon by 85 the differential between the exhaust pressure and atmospheric pressure will be decreased and the spring will exert an increasing influence upon the regulation and maintain the degree of exhaust within the instrument 90 at a lower level, that is to say, at a point farther below atmospheric pressure.

The position of the fulcrum of the regulator pneumatic 7, which is determinable by the position of the rollers 17, therefore determines the regulation and the intensity of 100 playing.

Extending from the block 15 is a rod 19 attached to the movable board of the expression bellows 20 so that as said bellows 105 20 is collapsed or expanded the roller 17 will be caused to move along the tracks 14 toward or away from the center of the pneumatic 7. The pneumatic 20 is arranged to be exhausted through a duct 21 preferably 110

having an adjustable bleed by which the capacity of the duct may be diminished so as to cause the pneumatic 20 to collapse slowly and thereby slowly and gradually move the fulcrum of the regulator pneumatic toward the left in the drawings to decrease the effective pull of exhaust upon the movable board of the pneumatic 7. The effect of this, as will be readily understood by those skilled in the art, is to modify the regulation so as to produce a gradual and slow crescendo. When atmosphere is admitted through the duct 21, the bellows 20 having been wholly or partially collapsed, is then expanded by a spring 22. This returns the block 15 to or toward the position shown in the drawings and thereby produces a slow diminuendo.

The bellows 20 may also be exhausted through a duct 23 of greater capacity than duct 21 to collapse the pneumatic 20 at a greater speed, but preferably the duct 23 is of such restricted capacity as to collapse the pneumatic 20 to give a crescendo effect similar to, but faster than that produced by exhausting through duct 21. When atmosphere is re-admitted through the duct 23 a fast diminuendo results.

The pneumatic 20 may also be exhausted through a duct 24 of sufficiently large capacity to permit the pneumatic to be exhausted practically instantaneously to move the block 15 rapidly toward the left in the drawings to produce a distinct step of increase in playing intensities. When atmosphere is re-admitted through the large capacity duct 24, the bellows 20 is expanded practically instantaneously to produce a distinct step of decrease in playing intensities.

40 To provide for a plurality of distinct steps, means are provided for arresting the collapse of the pneumatic 20 intermediate its two extreme positions herein illustrated. Means are shown for arresting the pneumatic at one intermediate position, but obviously a plurality of such means may be provided if desired. The movable board of the expression pneumatic 20 carries at its outer end a lug 25 arranged to contact with 50 the stop device presently to be described.

A pneumatic 26 is arranged to be exhausted through a duct 27 and is provided with a stop 28 adapted to be interposed in the path of movement of the lug 25 upon the movable board of the expression pneumatic 20, and, for example, to arrest the movement thereof when the pneumatic 20 is approximately half collapsed.

When the stop 28 is not interposed in the 60 path of movement of the lug 25, the expression bellows 20 will be completely collapsed. If atmosphere is admitted thereto to permit expanding movement the stop 28 may be interposed in the returning path of 65 the lug 25 so as to arrest the expanding

movement of the expression bellows 20, at approximately one half thereof. If thereafter atmosphere is admitted to bellows 26 the stop 28 will be withdrawn from contact with the lug 25 by spring 29 fast to the movable board of the pneumatic 26 and the expression bellows 20 will be permitted to expand to its full capacity.

The expression bellows 20 may thus be collapsed at any one of several speeds and 75 to different extents to produce corresponding increases in playing intensities, and likewise the expression bellows 20 may be expanded at any one of several speeds and through different extents to produce corresponding 80 decreases in playing intensities.

The increases or decreases in playing intensities may be by way of crescendo and diminuendo at different speeds, or may be by practically instantaneous distinct steps. 85 All the effects described are produced in the apparatus by moving the fulcrum of the regulator pneumatic and thereby modifying the regulation so as to produce a change in the action of the regulator upon the valve 8. 90

The various ducts 21, 23, 24 and 27 may be controlled in any practicable manner by any suitable automatic means preferably controlled by vents in the tracker. For instance, the so-called automatic actions described in Patent No. 1,008,291 may be adapted for this purpose. These automatic actions and valves form in themselves no part of this invention and therefore need not be described or shown herein.

100 It is to be understood that this invention is not limited to the particular construction, organization and mode of operation shown in the drawings and described for illustration. On the contrary, the invention may 105 be variously embodied and the particular construction may be variously modified within the scope of the subjoined claims. It is not indispensable that all the features of the invention be used conjointly since, in 110 some instances, they may be used separately to advantage.

I claim as my invention:

1. In a musical instrument, the combination of playing pneumatics; a source of 115 power for operating the playing pneumatics; a valve between said source of power and the playing pneumatics; a regulator pneumatic comprising a movable member having a fulcrum, said movable member being operatively connected to said valve; means to expand the regulating pneumatic against the action of the operating power; and means to vary the position of the fulcrum of the regulating pneumatic to vary the regulation 120 thereby.

2. In a musical instrument, the combination of playing pneumatics; a source of power for operating the playing pneumatics; a valve between said source of power and 125

- the playing pneumatics; a regulator pneumatic comprising a movable member having a fulcrum, said movable member being operatively connected to said valve; means to 5 expand the regulating pneumatic against the action of the operating power; an expression bellows; and means for varying the position of the fulcrum of said regulating pneumatic by the collapse of said expression bellows.
3. In a musical instrument, the combination of playing pneumatics; a source of power for operating the playing pneumatics; a valve between said source of power and the playing pneumatics; a regulator pneumatic comprising a movable member having a fulcrum, said movable member being operatively connected to said valve; means to 10 expand the regulating pneumatic against the action of the operating power; means for shifting the relative position of the fulcrum of the regulating pneumatic by the collapse of said expression bellows.
4. In a musical instrument, the combination of playing pneumatics; a source of power for operating the playing pneumatics; a valve between said source of power and the playing pneumatics; a regulator pneumatic comprising a movable member having 15 a fulcrum, said movable member being operatively connected to said valve; means to expand the regulating pneumatic against the action of the operating power; and means for shifting the relative position of the fulcrum of the regulating pneumatic, gradually to produce a crescendo.
5. In a musical instrument, the combination of playing pneumatics; a source of power for operating the playing pneumatics; a valve between said source of power and the playing pneumatics; a regulator pneumatic comprising a movable member having 20 a fulcrum, said movable member being operatively connected to said valve; means to expand the regulating pneumatic against the action of the operating power; and means for shifting the relative position of the fulcrum of the regulating pneumatic, gradually to produce a crescendo.
6. In a musical instrument, the combination of playing pneumatics; a source of power for operating the playing pneumatics; a valve between said source of power and the playing pneumatics; a regulator pneumatic comprising a movable member having a fulcrum, said movable member being operatively connected to said valve; means to 25 expand the regulating pneumatic against the action of the operating power; and means for shifting the relative position of the fulcrum of the regulating pneumatic, gradually to produce a crescendo.
7. In a musical instrument, the combination of playing pneumatics; a main source of power for operating the playing pneumatics; a valve between said main source of power and the playing pneumatics; a regulating pneumatic having operative connection with said valve and means providing a movable fulcrum for said regulating pneumatic.
8. In a musical instrument, the combination of playing pneumatics; a main source of power for operating the playing pneumatics; a valve between said main source of power and the playing pneumatics; a regulator pneumatic comprising a movable member having a fulcrum, said movable member being operatively connected to said valve; and means to vary the position of said fulcrum to vary the regulation thereby varying playing intensities.
- In testimony whereof, I have signed my name to this specification this twenty first day of September, 1916.

CHARLES F. STODDARD.
